[57] CLAIM

The ornamental design for a three-position swing, as shown and described.

DESCRIPTION

FIG. 1 is a perspective view of a three-position swing embodying my new design;

FIG. 2 is a top plan view thereof;

FIG. 3 is a view in side elevation taken perpendicular to the plane defined by one leg of the swing, all sides not shown being substantially identical;

FIG. 4 is an elevational view of the swing showing one leg in end elevation; and

FIG. 5 is an elevational view, as shown from the side opposite FIG. 4.
